UNITED STATES PATENT OFFICE

2,371,028

LIQUID DISPENSING DEVICE

Andrew F. Christ, Milwaukee, Wis.

Application July 28, 1941, Serial No. 404,423

1 Claim. (Cl. 225—9)

My invention relates to dispensing devices and more particularly to faucets for dispensing draught beer or the like. The object of my invention is to produce a device that will dispense raw draught beer without the usual foam caused by carbonation and permitting the deposit of a pre-determined quantity of foam into the container onto the top of the raw beer.

Another object of my invention is to produce a device of the character described, that employs the customary attaching means to the barrel or keg acting as a container or supply reservoir for the beer, and permitting any conventional type of tapping mechanism.

A further object of my invention is to provide a faucet that has a three stage adjustment, thereby making it possible for the operator to manipulate the lever of the faucet much in the same manner as any conventional type of faucet.

Still another object of my invention is to so construct the device as to permit its being cleaned without a great amount of labor, there being comparatively few parts and all made readily accessible in their assembly.

Other and further objects of my invention will become more apparent as the description proceeds when taken in conjunction with the drawings in which

Figure 1 is a perspective side view of the tank showing the piping and faucet arrangement, and illustrating the feed pipe and tubular coil within the tank in phantom.

Figure 2 is a fragmentary cross-sectional view of the tank, pipe and coil structure taken at line 2—2 in Figure 1.

Figure 3 is a cross-section of the tube assembly taken at line 3—3 in Figure 1.

Figure 4 is a fragmentary cross-sectional view of the tubular assembly and connecting fixture.

Figure 5 is a cross-section of the connecting fixture taken at the line 5—5 in Figure 4.

Figure 6 is a fragmentary cross-section of the faucet construction taken at line 6—6 in Figure 7.

Figure 7 is a cross-sectional view of the faucet taken at line 7—7 in Figure 6 and showing the three stages of the lever during the operation of the faucet.

Figure 8 is a cross-section of the faucet shown in Figures 6 and 7 taken at line 8—8 of Figure 6.

Figure 9 is a cross-sectional view taken at the line 9—9 in Figure 8, and

Figure 10 is a perspective view of the barrel of the faucet, illustrating its tapered construction and the port arrangement for the separate dispensing of beer and foam.

Similar characters of reference indicate corresponding parts throughout the several views and referring now to the same, the character 10 shows a tank of cylindrical shape provided with a conical cover 11 attached to the tank 10, by means of a plurality of bolts 12.

If desired a gasket not shown may be placed between the tank 10 and the cover 11 or any desirable means may be employed for retaining an air-tight seal. There is an inlet tube 13 angularly disposed through the wall of the tank 10 in a manner to permit the beer entering the tank 10 from the keg or receptacle to assume a radial path against the inner face of the wall of the tank 10, and a vertical tube 13' entering the bottom of the tank 10, to permit beer entering the tank 10 to flow upward against the cover 11. The cover 11 is shown with an outlet tube 14 centrally disposed in its apex. The tube 14 leads directly to a faucet assembly 15 and is provided with connecting units 16. A spiral coil 17 consisting of a tube smaller in diameter than the outlet tube 14 circles around the vertical tube 13' and has its inlet within the tank 10 near its bottom as shown at 18 and the outlet end of the coil 17 terminates into a tube 19 which is disposed within the tube 14 as shown in Figure 3 and extends with it to the faucet assembly 15. In Figure 4 is shown a connecting unit 16 illustrating the manner in which the tube 19 is disposed within the outer tube 14. The connecting unit 16 consists of a member 20 engaging the outer tube 14 by means of a threaded portion at 23. An outer member 24 having an inner thread engages the member 20 at 25 and acts as a clamping means to retain the member 22 in position. Obviously a gasket or washer 26 as shown may be employed to seal the contact of the two members 20 and 22. This same construction may be employed in as many connecting units as may be used in the proper installation of the device.

The member 20 is provided with an aperture 21 in its central portion through which the tube 19 passes and a plurality of smaller ports or apertures 28 surround the center aperture 21 as shown in Figures 4 and 5.

The faucet assembly 15 consists of an outer shell 29 engaging the outer tube 14 at 30 by means of a thread, and the tube 19 at 31 as shown. The depending end of the shell 29 terminates into a dual spout arrangement having two outlets 32 and 33 respectively. There is a revolving barrel 34 as shown in Figure 10. This barrel 34 is of cylindrical contour tapered smaller at one end and engages a tapered hole in the shell 29. The

barrel 34 is held in close contact with the body of the shell 29 in the tapered hole by means of a resilient member 35 and is revolved in a radial path by means of a lever 36 slidably engaging one end 37 of the barrel 34 and held in position by means of two nuts 38 and 39 respectively. The barrel 34 is further provided with a segmental section 40 near one end. This section 40 is arranged to permit contact with a resilient member 41 fastened at one end to the shell 29 by means of a screw 42 and inserted into an enclosure 43 recessed for the purpose into the shell 29 as shown.

A port 44 is transversely disposed through the entire diameter of the barrel 34 and in proper alignment with the tube 19 and spout 33 and a port 45 also transversely disposed and in proper alignment with the ports 46 in the spaces between tubes 14 and 19 and the spout 32. This port 45 is provided at its outlet with a plurality of apertures 47 as shown in Figure 10. Both ports 44 and 45 are spaced in direct angular relation with one another and with the segmental section 40 so that either port 44 or 45 are in direct alignment with their respective supply ports and outlet ports. When the lever 36 is in a position as indicated at 48 shown in phantom in Figure 7 the port 44 in the barrel 34 is in direct alignment with the tube 19 and the spout 33 while when the lever 36 is in position as indicated at 49 in Figure 7 the port 45 is in direct alignment with the port 46 and the spout 32.

It is manifest to anyone familiar with the art that the member 20 may be constructed with a separate insert incorporating the apertures 27 and 28 or the member 20 may be constructed integral as shown in Figure 4.

In operation the device functions as follows. The entire device is connected to a barrel or keg of beer in the conventional manner by means of a tube leading to either the inlet tube 13 or the tube 13' of the tank 10. If the former inlet is employed, the tube 13' will be closed by a conventional screw closure cap (not shown), and vice versa. The pressure applied to the barrel or keg containing the beer will cause the beer when entering the tube 13 in the tank 10 to flow in a circular path against the wall within the cylindrical structure, and the foam caused by carbonation and pressure will find its way to the top of the tank 10 immediately below the cover 11, and when the beer enters the tank 10 through the vertical tube 13' it will flow upward against the inside of the cover 11, causing the foam to rise to the top of the tank 10 immediately below the cover 11. With the lever 36 in a neutral position, that is, vertical as shown in Figure 7, the faucet 15 will be closed and when the lever 36 is pulled forward as shown in the position 48 in Figure 7 the port 44 will properly align with the tube 19 and the spout 33. The beer in the tank 10 will be forced

through the coil 17 at its inlet 18 near the bottom of the tank 10 and the horizontal spiral shape of the coil 17 will cause raw, flat beer to be dispensed at the spout 33. When the lever 36 of the faucet 15 is pushed rearward into the position as shown at 49 in Figure 7 the port 45 will be aligned with the aperture 46 and the spout 42 causing the foam which has accumulated at the top of the tank 10 to enter the tube 14 between its inner face and the inner tube 19, and the pressure will force the foam through the plurality of apertures 28 and the reduced apertures 47 in the barrel 34 and it will then be dispensed through the spout 32 of the faucet 15.

In this manner it is possible to draw raw beer from the keg when the lever is in position as shown at 48 and any desired amount of foam may be placed on to the raw beer when the lever is placed in position as shown at 49 in Fig. 7.

I have entered into a detailed description of the construction and relative arrangement of parts embraced in the embodiment of my invention in order to impart a full, clear and exact understanding of the said embodiments. I do not desire however to be understood as confining myself to the said specific construction and relative arrangement of parts inasmuch as in future practice of the invention various changes and modifications may be made that fall within the scope of the appended claim.

Having thus described my invention what I claim and desire to secure by Letters Patent in the United States is:

A device of the character described, comprising a cylindrical enclosure, a cover for said enclosure, an inlet and outlet port for said enclosure, a spiral coil centrally disposed within said enclosure, said coil having its inlet near the bottom of said enclosure and its outlet disposed centrally within the outlet of said enclosure, the tube comprising said coil having a smaller outside diameter than the inside diameter of the outlet of said enclosure, providing a space between the outer face of said tube and the inner face of said outlet, in combination with a faucet, said faucet comprising a shell, a barrel mounted within said shell, a lever outside of said shell and revolving said barrel, a main port transversely arranged through said barrel, an auxiliary port transversely arranged through said barrel, a tube leading to said faucet from the outlet of said enclosure, a tube leading from the spiral coil within said enclosure to said faucet inside of the tube leading from the outlet of said enclosure, the ports within the barrel of said faucet arranged for alignment with said tubes, said faucet being provided with two outlet ports registering with the ports within said barrel, when in alignment with the tubes leading from said enclosure to said faucet.

ANDREW F. CHRIST.
